UNITED STATES PATENT OFFICE.

FRANK E. JOHNSON, OF SALT LAKE CITY, UTAH, ASSIGNOR TO AMERICAN MANGANESE STEEL COMPANY, OF AUGUSTA, MAINE, A CORPORATION OF MAINE.

MILL-LINER.

1,207,174.

Specification of Letters Patent.

Patented Dec. 5, 1916.

Application filed May 27, 1916. Serial No. 100,212.

To all whom it may concern:

Be it known that I, FRANK E. JOHNSON, a citizen of the United States, and a resident of Salt Lake City, in the county of Salt Lake and State of Utah, have made and invented certain new and useful Improvements in Mill-Liners, of which the following is a specification.

My invention relates to liners for tube, ball, and other types of mills, and particularly to that class of liners composed of detachable lining plates and sectional lifting bars.

In practice, and especially in mills where large balls or pebbles are used, it has been found that the cascading action causes wear upon the rear surface of the lifting bars, as well as upon the front sides thereof, and also that the lifting bars are subject to forward, as well as rearward, thrusts, due to this cascading action.

It is therefore an object of the present invention to provide a liner wherein the wear sections of the lifting bars extend over both sides of the base sections and coöperate with the lining plates, so as to successfully withstand either forward or rearward thrusts and completely protect both sides of the base or filler section from wear.

A further object is to provide a liner which is so constructed that the mill can be rotated in either direction, and with the wear sections of the lifting bars so designed that they may be reversed.

A further object is to provide a mill liner possessing the above-mentioned characteristics, in which the lining plates can stretch or elongate, without danger or likelihood of bursting the mill shell.

A further object is to provide a mill liner in which the wearing sections of the lifting bars may be easily removed or replaced, and, when securely locked in position, aid in holding the lining plates in place.

Other objects and advantages will appear as the description proceeds, wherein it is to be understood that changes in the precise embodiment of the invention can be made within the scope of what is claimed without departing from the spirit thereof.

The preferred embodiment of my invention is disclosed in the accompanying drawings, wherein:

Figure 1 is a view in vertical section, of

a portion of a mill equipped with my improved liner; Fig. 2 is a detailed view in perspective of one of the lining plates; Fig. 3 is a detailed view in perspective of the base or filler section of the lifting bars; Fig. 4 is a detailed view in perspective of the top wear section of a lifting bar; Fig. 5 is a view in section of a liner, wherein the top wear section of each lifting bar engages but one of the adjacent lining plates; Fig. 6 is a detail view in section, of a liner which is so constructed that the wear section of the lifting bar is held in place along one edge by one of the adjacent lining plates; Fig. 7 is a fragmental view in section of a liner wherein the edges of the lining plates project up, and form a continuation of, the sides of the wear sections of the lifting bars; Fig. 8 is a fragmental view in vertical section of a liner wherein the sides of the wear sections of the lifting bars extend between the edges of the adjacent lining plates; Fig. 9 is a view in section of a mill liner similar to that illustrated in Fig. 8, the filler bar, in the present instance, being of trapezoidal contour or outline.

Referring specifically to the several views, the mill liner is formed with the detachable lining plates 10, the edges 11 of which thicken to form the ribs 12. Interposed between the lining plates, are the sectional lifting bars 13, which latter, as the mill is rotated, cause the contents to cascade and produce the required grinding and pulverizing action.

Each lifting bar is formed with a base or filler section 14, having beveled sides 15. A top wear section 16, preferably formed of some hard wear-resisting metal, such as manganese steel, is superposed upon the base section, and is formed with inclined sides 17, contacting and embracing both beveled sides of the base section. The base and top sections of the lifting bars are provided with registering openings 18, through which extend suitable bolts or other securing means 19, resulting in the rigid securing of the lifting bars in place, and at the same time allowing them to be easily removed and the top or wear sections reversed or replaced, as may be necessary.

The sides of the top or wear sections of the lifting bars extend down to, and contact with, the beveled surfaces of the ribs

80

105

11, which are formed at the edges of the lining plates, and accordingly aid in holding the lining plates in place. The lining plates, while extending into close proximity to the 5 bases of the lifting bars, stop just short thereof, and accordingly allow the lining plates to elongate or expand without subjecting the mill shell to severe bursting strains. While the holding action of the lifting bars

10 may alone be relied upon to secure the lining plates 10 in place, I have illustrated the lining plates and the mill shell as being provided with openings 21, through which extend suitable holding bolts 20, although the 15 presence of these openings and the use of these bolts may be omitted if desired.

The liner disclosed in Fig. 5 is formed with the lining plates 22, and the sectional lifting bars 23. The base section 24 of each 20 lifting bar receives a wear section 25 thereon, the latter being of somewhat irregular shape and including the overhanging sides 26—27, which embrace the sides of the base section therebetween. The rear side 26 of 25 the wear section projects outwardly and downwardly, and bears upon the toe end 28 of the adjacent lining plate, while the front side 22 of the wear section projects between the heel end 29 of the adjacent lining plate 30 and the base section 24 of the lifting bar. Although this type of wear section may not be reversed, the mill may be operated in either direction, as the sides of the wear section completely protect both sides of the base 35 section. The base section is accordingly protected against the direct thrusts and wear resulting from lifting the contents of the mill as the latter is rotated, and from the indirect action resulting from the cascading 40 of the mill contents as it strikes against the opposite or rear side of the lifting bar.

In some instances, it is desirable that the lining plates coöperate to hold the lifting bars in place, and with this in view I provide a liner as disclosed in Fig. 6, wherein the mill 30 of each lining plate is provided with an overhanging ledge 31, beneath which projects a flange 32, carried by the one side of the wear section 31 of the lifting 45 bar 34. A base or filler section 35 receives this top or wear section thereon. The toe end of the adjacent lining plate is enlarged 50 to form a rib 36, between which, and the base section 35, the remote side of the wear section projects.

The modified forms of mill liners illustrated in Figs. 7, 8 and 9, are used where it is not essential that the lining plates and lifting bars coöperate to prevent their mutual inward displacement. The form disclosed in Fig. 7 has the lining plates 40 provided at their edges with the raised and beveled ribs 41, these ribs forming a continuation of the outer surfaces of the wear 60 sections 42 of the lifting bars. The sides 43

of the wear sections extend down, and embrace, the outer portions of the base or filler sections 44, which, in connection with the raised ribs 41, completely protect and house the base or filler sections. The wear sections in this form of liner are reversible, and the construction is such that the mill may be operated in either direction. A somewhat similar construction is illustrated in Fig. 8, wherein the base section 50 is 70 substantially rectangular in cross-section, and the sides 51 of the reversible wear section 52 project nearly to the outer wall of the base section and extend between the said base section and the adjacent edges of the 75 lining plates 53. A similar modification is illustrated in Fig. 9, wherein the base or filler section 60 is substantially trapezoidal in cross-section, and the sides 61 of the top or wear section 62 are correspondingly bevelled. 85

In each of the various forms of liners above described, suitable bolts (not shown), similar to the bolts 19 illustrated in Fig. 1, are employed and extend through registering openings (not shown) in the wear and base sections of the lifting bars, and are secured to the mill shell, so as to hold the lifting bars rigidly in place, and at the same time allow them to be readily removed or 95 reversed as may be desired.

What I claim is:—

1. A liner comprising lining plates, lifting bars interposed therebetween, said lifting bars formed with base sections and with 100 wear sections, said lining plates and lifting bars completely housing said base sections.

2. A mill liner comprising lining plates, lifting bars interposed therebetween, said lifting bars formed with base sections spaced 105 from the edges of the adjacent lining plates, and wear sections, mounted upon said base sections, secured thereto and projecting to opposite sides thereof.

3. A mill liner comprising lining plates, lifting bars interposed therebetween, said lifting bars formed with base sections with beveled outer edges, and wear sections with inclined sides mounted upon said base sections, extending down to, and contacting 115 with, the adjacent lining plates and means for holding said bars in place.

4. A mill liner consisting of lining plates, lifting bars interposed therebetween and formed with base sections, and wear sections detachably mounted thereon and provided with spaced walls receiving the said base sections therebetween, and means for securing said lining plates and lifting bars in place. 120

5. A mill liner comprising lining plates, lifting bars interposed therebetween, said lifting bars consisting of base sections, wear sections mounted upon said base sections and projecting thereabove, said wear sections 125 130

provided with spaced sides projecting to both sides of said base sections and embracing the same therebetween, adapted to protect both sides of said base sections, and allow the mill to be operated in both directions, and means for anchoring said lining plates and lifting bars in place.

Signed at Chicago in the county of Cook and State of Illinois this 24th day of May, A. D. 1916.

FRANK E. JOHNSON.
